United States Patent Office.

GEORGE H. SANBORN, OF BOSTON, MASSACHUSETTS.

Letters Patent No. 76,947, dated April 21, 1868.

IMPROVEMENT IN CIRCULAR-SAW TABLES.

The Schedule referred to in these Letters Patent and making part of the same.

TO ALL WHOM IT MAY CONCERN:

Be it known that I, GEORGE H. SANBORN, of the city of Boston, in the State of Massachusetts, have invented certain new and useful Improvements in Bookbinders' Sawing-Machines; and I do hereby declare the following to be a full and correct description of the same, reference being had to the accompanying drawings, in which—

Figure 1 is a perspective view of the machine, the table being shown in its elevated position, in order to display the parts beneath it.

Figure 2 is a detail view of a portion of the gauge.

Figure 3 is a similar view, showing the mode of attachment of the slats which separate the saw-blades.

The same letter indicates the same part wherever it occurs.

This invention relates to that class of machines used by bookbinders for sawing the grooves for holding the threads, and those for the catch or kettle-stitch.

My improvements consist in a new mode of attaching and counterpoising the table, so that it can be more conveniently raised and lowered; in a more secure method of attaching the slats to the table; and in the combination with the table of an adjustable gauge, all as hereinafter set forth.

To enable others to make and use my improved sawing-machine, I will proceed to describe its construction and operation.

In the drawings, A marks an iron frame by which the operative parts of the machine are supported. B is a large friction-pulley, turned by means of handle C, and bearing against band D, travelling over pulleys E and F, the latter of which is on the end of the saw-shaft G. This driving-mechanism may be varied at pleasure. On the shaft G are placed a number of saws S S, separated from each other by sleeves H, placed on the saw-shaft, the distance of the saws from each other depending on the length of the sleeves, which may be varied according to the requirements of the work to be done. The periphery of the saws projects above the surface of the table T, through an opening, J, in the table. The saw-shaft is held in an adjustable frame, X, which can be raised and lowered by set-screws, or in any suitable manner, to regulate the projection of the saws above the surface of the table. The table T is hinged to the frame at h, and may either lie in a horizontal position on the frame, or be raised to a vertical or any intermediate position, as may be desired. The table is usually made of iron, and is quite heavy, and to facilitate the handling of it, I attach to it, by cords R, passing over pulleys P, a counterpoise, W, of sufficient weight to relieve the movement of the table on its hinges of all difficulty. The final adjustment of the position of the table, when nearly down in contact with the frame, is made by wedges w, sliding in the trough V, operated by a screw, and working against the inclined faces of similar wedges opposite in position, attached to the under side of the table. Lugs U, passing inside the frame, and in contact with it when the table approaches its lowest position, tend to prevent any lateral movement of the table when down. The opening J in the table, through which the saws project, receives any number of slats K that may be required to fill the spaces between the saws, and preserve the continuity of the surface of the table, except as regards the slits in which the saws work. It is desirable that these slats should be easily inserted and removed, and yet be firmly and securely held when in place. Their construction and mode of attachment are clearly shown in fig. 3. They have a bevel, e, at one end, corresponding with a groove of similar shape in the table, and a groove, d, in the opposite end, which receives the edge of bar L, which works in a recess in the table made to receive it, and is forced into the groove d, by a spring or springs, s, of any convenient form or material. By pressing back the bar L, the slats are readily released or inserted, and, when in place, they are securely held.

To the top of the table I attach a gauge, M, by means of the parallel bars N, to which the gauge is pivoted at p p. The bars N are pivoted at p' p' to lugs projecting from the edge of the table. A curved slot, a, receives a screw which projects up through it from the bar N, and takes a clamping-nut, which serves to clamp the gauge at any required position.

Having thus fully described my invention, what I claim, and desire to secure by Letters Patent, is—

The spring-bar L, in combination with the grooved slats K, arranged and operating as described.

The above specification of my said invention signed and witnessed at Boston, this 17th day of October,

A. D. 1867.

GEO. H. SANBORN.
